[57] ABSTRACT

The control device has a drive circuit, in turn having a number of modular circuits—one for each inductor—activated selectively and receiving timing signals, and a common circuit connected to the modular circuits and cooperating with the activated modular circuit to supply the respective inductor. Each modular circuit has a first controlled switch connected between a first input terminal and a respective first output terminal, and a second controlled switch connected between the respective first output terminal and a storage capacitor; and the common circuit has a third controlled switch connected between the storage capacitor and a respective second output terminal, and cooperating with the second controlled switch to selectively transfer energy between the storage capacitor and the respective inductor.

DEVICE FOR CONTROLLING INDUCTIVE LOADS, IN PARTICULAR OF INJECTORS OF AN INTERNAL COMBUSTION ENGINE INJECTION SYSTEM

BACKGROUND OF THE INVENTION

The present invention relates to a device for controlling inductive loads, in particular of injectors of an internal combustion engine injection system.

As is known, to control the injectors of an internal combustion engine injection system, each injector must be supplied with current, the curve of which comprises a rapidly increasing portion, a more slowly increasing portion, a portion decreasing to a hold value, a portion oscillating about the hold value, and a portion decreasing to zero.

To achieve such a curve, control devices are currently employed whereby the inductive loads of the injectors are connected on one side to a low-voltage supply source, and on the other side to a ground line via a controlled electronic switch. A major drawback of control devices of this sort is that, in the event of ground shorting of one of the terminals of any one of the inductive loads—e.g. due to impaired insulation of an injector conductor, and contact between the conductor and the vehicle body—the injector and/or control device is irreparably damaged and the engine is turned off—an extremely dangerous situation when the vehicle is moving.

To eliminate the above hazard, control devices have been proposed whereby the inductive loads of the injectors are grounded on one side and connected on the other side to an internal node of the control device itself, so that, as opposed to damaging the control device and turning off the engine, ground shorting of one of the terminals of the inductive loads simply results in that particular injector being put out of use, so that the vehicle continues running minus one injector.

Such control devices, however, in addition to involving complex, high-cost circuitry, normally fail to provide for simultaneously injecting different cylinders, as required for example by engine injection systems involving multiple injection of each cylinder.

SUMMARY OF THE INVENTION

It is an object of the present invention to provide a straightforward, low-cost control device designed to overcome the aforementioned drawbacks.

According to the present invention, there is provided a device for controlling inductive loads, in particular of injectors of an injection system of an internal combustion engine, comprising:

timing means generating timing signals for controlling said injectors;

drive means for driving said inductive loads and comprising a number of modular circuits, one for each inductive load; said modular circuits being activated selectively and receiving said timing signals;

said drive means also comprising a common circuit comprising energy storing means; said common circuit being connected to the modular circuits and cooperating with the activated modular circuit to supply a respective inductive load;

said drive means also comprising a first and a second input terminal respectively connected, in use, to a positive pole and a negative pole of a supply source; and a number of pairs of output terminals, one for each injector; each pair

of output terminals comprising a first and a second output terminal between which a respective inductive load is connected in use;

characterized in that each of said modular circuits comprises, in combination:

first controlled switching means connected between said first input terminal and a respective first output terminal of said drive means; and

second controlled switching means connected between said respective first output terminal and said energy storing means;

and in that said common circuit comprises:

third controlled switching means connected between said energy storing means and a respective second output terminal of said drive means; said third controlled switching means cooperating with said second controlled switching means to permit selective transfer of energy between said energy storing means and said respective inductive load.

BRIEF DESCRIPTION OF THE DRAWINGS

A preferred, non-limiting embodiment of the present invention will be described by way of example with reference to the accompanying drawings, in which:

FIG. 1 shows a block diagram of an injection system comprising a control device in accordance with the present invention;

FIG. 2 shows a circuit diagram of the FIG. 1 control device;

FIGS. 3 to 7 show time graphs of quantities relative to the FIG. 2 control device.

DETAILED DESCRIPTION OF THE INVENTION

Number 1 in FIG. 1 indicates a device for controlling the control electromagnets of injectors 3 of an injection system 4 of an internal combustion engine 5, in particular a supercharged diesel engine. In FIG. 1, the control electromagnets are represented by the electric equivalents comprising inductors 2.

Control device 1 comprises a timing circuit 6 receiving information signals S measured on engine 5, and generating timing signals T for controlling injectors 3; and a modular circuit 7 receiving timing signals T and for driving injectors 3 accordingly.

Modular circuit 7 comprises a number of modular circuits 10, one for each inductor 2, activated selectively and receiving timing signals T as described in detail later on; and a common circuit 11 connected to modular circuits 10 and cooperating with the activated modular circuit 10 to supply respective inductor 2 as also described in detail later on.

More specifically, modular circuit 7 comprises a supply line 12; a ground line 13; and a first and second connecting line 14, 15 between modular circuits 10 and common circuit 11.

Modular circuit 7 also comprises a first and second input terminal 16, 17 respectively connectable to a positive pole and a negative pole of a supply source, e.g. a battery 18; and a number of pairs of output terminals, one for each injector 3. Each pair of output terminals comprises a first and second output terminal 19, 20 between which a respective inductor 2 is connected in use. More specifically, the first input terminal 16 of modular circuit 7 is connected to supply line 12, and the second input terminal 17 and the second output terminals 20 are connected to ground line 13.

Each modular circuit **10** comprises a MOSFET charging transistor **21** having a control terminal connected to timing circuit **6** and receiving from timing circuit **6** a first timing signal T_1 , a drain terminal connected to supply line **12**, and a source terminal connected to the anode of a charging diode **22**, the cathode of which is connected to a respective first output terminal **19** of modular circuit **7**.

Modular circuit **10** also comprises a MOSFET discharging transistor **23** having a control terminal connected to timing circuit **6** and receiving from timing circuit **6** a second timing signal T_2 , a drain terminal connected to first connecting line **14**, and a source terminal connected to respective first output terminal **19** of modular circuit **7**.

Modular circuit **10** also comprises a clamping diode **24** with the anode connected to second connecting line **15**, and the cathode connected to respective first output terminal **19** of modular circuit **7**.

Common circuit **11** comprises a capacitor **25** having a first and second terminal connected respectively to first connecting line **14** and second connecting line **15**.

Common circuit **11** also comprises a MOSFET recirculating transistor **26** having a control terminal connected to timing circuit **6** and receiving from timing circuit **6** a third timing signal T_3 , a drain terminal connected to ground line **13**, and a source terminal connected to the anode of a recirculating diode **27**, the cathode of which is connected to second connecting line **15**.

Common circuit **11** also comprises a discharging diode **28** with the anode connected to ground line **13**, and the cathode connected to first connecting line **14**.

The drain and source terminals of each transistor **21**, **23**, **26** of modular circuits **10** and common circuit **11** are connected respectively to the cathode and anode of a respective protection diode **29** operating in known manner and therefore not described in detail.

Timing circuit **6** selectively activates each modular circuit **10** by supplying the control terminals of transistors **21**, **23**, **26** with timing signals T_1 , T_2 , T_3 , which are only supplied to the modular circuit to be activated, so that the other modular circuits **10** remain off. Furthermore, timing signals T_1 , T_2 , T_3 , control MOSFET transistors **21**, **23**, **26** to saturate them or to switch them off, so that each transistor acts as a closed or open switch.

Operation of control device **1** will now be described with reference to one injector **3** and one modular circuit **10**—the other modular circuits operating in the same way—which cooperates with common circuit **11** to supply respective inductor **2**, and with specific reference to FIGS. **3** to **7** showing time graphs of timing signals T_1 , T_2 , T_3 of transistors **21**, **23**, **26**, the voltage V_C of capacitor **25**, and the current flow I_L in inductor **2**.

To begin with, timing circuit **6** opens all of transistors **21**, **23**, **26**, so that both modular circuit **10** and common circuit **11** are off.

Timing circuit **6** then closes and opens, several times in succession, the charging transistor **21** of the modular circuit **10** activated at the time, by supplying the control terminal of charging transistor **21** with a train of so-called recharging pulses, as shown in FIG. **3** (RECHARGING PHASE). More specifically, when charging transistor **21** is closed (instant t_0 in FIG. **3**), a closed loop is formed comprising battery **18**, charging transistor **21**, charging diode **22** and inductor **2**; and inductor **2**, being supplied by battery **18** with a constant voltage, is supplied with an increasing current, which increases the energy stored in inductor **2**.

When charging transistor **21** is opened (instant t_1 in FIG. **3**), current flow in the above loop is cut off so that energy ceases to be stored in inductor **2**; and the time interval t_1-t_0 in which charging transistor **21** is closed is so calculated that the energy stored in inductor **2** is insufficient to open respective injector **3**.

When charging transistor **21** is opened, capacitor **25** and inductor **2** are connected to each other in series via discharging diode **28** and clamping diode **24** to form a resonant circuit, so that current flows in the loop defined by inductor **2**, discharging diode **28**, capacitor **25** and clamping diode **24**, thus charging capacitor **25** and increasing the voltage at the terminals of capacitor **25**, so that the energy stored in inductor **2** is transferred, minus any losses, to capacitor **25**.

As shown in FIG. **6**, by closing and opening charging transistor **21** several times in succession, the voltage at the terminals of capacitor **25** (which is assumed to have been precharged in previous drive cycles and therefore at an initial voltage value of other than zero) gradually increases to a predetermined value V_1 calculated to permit control of inductor **2** of injector **3**; and, as shown in FIG. **7**, the current flow in inductor **2**, as the inductor is charged and discharged, assumes a saw-tooth pattern.

Timing circuit **6** then closes recirculating transistor **23** and discharging transistor **26** sequentially (instant t_2 in FIGS. **4** and **5**) to form a further closed loop comprising capacitor **25**, inductor **2**, transistors **23**, **26** and recirculating diode **27**, and so form a further resonant circuit, so that a current flow is generated to discharge capacitor **25**, reduce the voltage at the terminals of capacitor **25**, and transfer all the energy stored in capacitor **25** to inductor **2**, as shown in FIG. **6** (RESONANT DISCHARGE PHASE).

As capacitor **25** is being discharged, the current flow in inductor **2** reaches a predetermined value I_1 calculated to open injector **3** instantaneously.

Upon the voltage at the terminals of capacitor **25** reaching a value V_2 equal to the voltage of battery **18** minus the threshold voltage of charging diode **22**, charging diode **22** begins conducting and again connects inductor **2** in series with battery **18**, which supplies inductor **2** with a constant voltage, so that the inductor is supplied with increasing current to keep injector **3** open (BYPASS PHASE). The current flow in inductor **2** therefore continues increasing, as shown in FIG. **7**, but at a slower rate than before.

After a predetermined time interval (t_{bypass} in FIG. **7**), by the end of which the current in inductor **2** has reached a predetermined value I_2 , timing circuit **6** opens discharging transistor **23** (instant t_3 in FIG. **4**), recirculating transistor **26** (instant t_4 in FIG. **5**) and charging transistor **21** (instant t_5 in FIG. **3**) to form a closed loop comprising capacitor **25**, inductor **2** (which combine to form a resonant circuit), clamping diode **24** and discharging diode **28**, and to generate a current flow to charge capacitor **25** and discharge inductor **2** (DELAY PHASE).

Discharging inductor **2** permits recharging of capacitor **25**, thus reducing the number of recharging pulses required in the next drive cycle, and hence recharging time, and also reducing the time interval between one injection and the next.

Rapid discharging of inductor **2** continues until timing circuit **6** closes recirculating transistor **26** (instant t_6 in FIG. **5**), at which point, the voltage at the terminals of capacitor **25** is at a value V_2 close to V_1 , and current flow in the loop is at a value I_3 below I_1 .

When recirculating transistor **26** is closed, inductor **2** and capacitor **25** are no longer connected in series, and current,

due to the energy stored in inductor 2, flows in the loop defined by inductor 2, recirculating transistor 26, recirculating diode 27 and clamping diode 24. In this phase, the current decreases at a slower rate than before (CHOPPER OFF PHASE).

After a predetermined time interval (instant t_7), timing circuit 6 closes and opens charging transistor 21 several times in succession by supplying a train of pulses to the control terminal, and the current flow in inductor 2 assumes a saw-tooth pattern oscillating about a predetermined mean value sufficient to keep injector 3 open. More specifically, timing circuit 6 closes charging transistor 21 (instant t_8), so that inductor 2 is once more connected in series with battery 18 via charging transistor 21 and charging diode 22; the current flow in inductor 2 therefore increases to charge 15 inductor 2 (CHOPPER ON PHASE) until timing circuit 6 opens charging transistor 21 (instant t_9 in FIG. 3) to disconnect inductor 2 from battery 18, so that current is supplied to the loop defined by inductor 2, recirculating transistor 26, recirculating diode 27 and clamping diode 24; which current partially discharges inductor 2 (CHOPPER OFF PHASE) until timing circuit 6 again closes charging transistor 21, and the CHOPPER ON PHASE is repeated.

Following injection, timing circuit 6 sequentially opens recirculating transistor 26 and charging transistor 21 (instants t_9 and t_{10} in FIGS. 5 and 6), so that capacitor 25 and inductor 2 are once more connected in series via clamping diode 24 and discharging diode 28 to form a resonant circuit, and the discharge current of inductor 2 charges and increases the voltage of capacitor 25 (RESONANT RECHARGING PHASE). This phase continues until inductor 2 is completely discharged, thus terminating the drive cycle of injector 3; at which point, timing circuit 6 may commence a further drive cycle of another injector 3 as described above.

The advantages of control device 1 are as follows. Firstly, by virtue of each inductor 2 being connected to control device 1 as described above, ground shorting of one of the terminals of inductor 2 in no way damages injector 3 or control device 1, but simply results in exclusion of injector 3, with no impairment in the operation of the other injectors 3, and without the engine suddenly being turned off.

Secondly, control device 1 provides for simultaneously driving a number of injectors 3, e.g. as in the case of multiple injections in some of the cylinders of engine 5. In fact, after the DELAY PHASE, during the CHOPPER ON and CHOPPER OFF PHASES of one injector 3, capacitor 25 is again charged and capable of enabling the RESONANT DISCHARGING phase to drive another injector 3.

Clearly, changes may be made to control device 1 as described and illustrated herein without, however, departing from the scope of the present invention.

We claim:

1. A device for controlling inductive loads comprising:
timing means for generating timing signals for controlling injectors;
drive means for driving said inductive loads and comprising:
a number of modular circuits, one for each inductive load, said modular circuits being activated selectively and receiving said timing signals;
a common circuit comprising energy storing means, said common circuit being connected to the modular circuits and cooperating with an activated modular circuit to supply a respective inductive load; and
a first input terminal and a second input terminal respectively connected, in use, to a positive pole and

a negative pole of a supply source and a number of pairs of output terminals, one for each injector, each pair of output terminals comprising a first output terminal and a second output terminal between which a respective inductive load is connected in use;

each of said modular circuits comprising, in combination:
first controlled switching means connected between said first input terminal and a respective first output terminal of said drive means; and
second controlled switching means connected between said respective first output terminal and said energy storing means;

said common circuit comprising:

third controlled switching means connected between said energy storing means and a respective second output terminal of said drive means, said third controlled switching means cooperating with said second controlled switching means to permit selective transfer of energy between said energy storing means and said respective inductive load.

2. A device as claimed in claim 1, said drive means also comprising a first reference potential line and a second reference potential line, and a first connecting line and a 25 second connecting line between said modular circuits and said common circuit; said first input terminal being connected to said first reference potential line; and said second input terminal and second output terminal being connected to said second reference potential line.

3. A device as claimed in claim 2, said first controlled switching means comprising first transistor means and a first unipolar switch connected to each other in series.

4. A device as claimed in claim 3, said first transistor means comprising a charging transistor, and said first unipolar switch comprising a charging diode.

5. A device as claimed in claim 4, said charging transistor having a control terminal connected to said timing means and receiving from said timing means a first of said timing signals, a first terminal connected to said first reference potential line, and a second terminal connected to an anode terminal of said charging diode; said charging diode having a cathode terminal respectively connected to said first output terminal of said drive means.

6. A device as claimed in claim 2, said second controlled switching means comprising second transistor means and a second unipolar switch, both having respective first terminals respectively connected together to said first output terminal of said drive means, and respective second terminals connected to said energy storing means.

7. A device as claimed in claim 6, said second transistor means comprising a discharging transistor, and said second unipolar switch comprising a clamping diode.

8. A device as claimed in claim 7, said discharging transistor having a control terminal connected to said timing means and receiving from said timing means a second of said timing signals, a first terminal connected to said first connecting line, a second terminal respectively connected to said first output terminal of said drive means; said clamping diode having an anode terminal connected to said second connecting line, and a cathode terminal respectively connected to said first output terminal of said drive means.

9. A device as claimed in claim 2, said third controlled switching means comprising third transistor means and a third unipolar switch connected to each other in series; said third controlled switching means also comprising a fourth unipolar switch connected between said first connecting line and said second reference potential line.

10. A device as claimed in claim **9**, said third transistor means comprising recirculating transistor; said third unipolar switch comprising a recirculating diode; and said fourth unipolar switch comprising a discharging diode **(28)**.

11. A device as claimed in claim **10**, said recirculating transistor having a control terminal connected to said timing means and receiving from said timing means a third of said timing signals, a first terminal connected to said second reference potential line, and a second terminal connected to an anode terminal of said recirculating diode; said recirculating diode having a cathode terminal connected to said second connecting line; and said discharging diode having an anode terminal connected to said second reference potential line, and a cathode terminal connected to said first connecting line.

12. A device as claimed in claim **2**, said energy storing means comprising a capacitive element connected between said first connecting line and said second connecting line.

13. A device as claimed in claim **1**, said first controlled switch means comprising a charging transistor; said second controlled switch means comprising a discharging transistor; said third controlled switch means comprising a recirculating transistor; and said charging transistor, said discharging transistor and said recirculating transistor being MOSFET transistors.

14. A device as claimed in claim **13**, further comprising a protection diode connected between first terminal and second terminal of each of said charging transistor, said discharging transistor and said recirculating transistor.
